(57) **CLAIM**

The ornamental design for an autonomous delivery vehicle with flying wing door carriage as shown and described.

DESCRIPTION

1. Autonomous delivery vehicle with flying wing door carriage

1.1 is a front elevation view of an autonomous delivery vehicle with flying wing door carriage embodying my new design;

1.2 is a rear elevation view thereof;

1.3 is a left side elevation view thereof;

1.4 is a right side elevation view thereof;

1.5 is a top plan view thereof;

1.6 is a top, front and left side perspective view thereof; and

1.7 is a top, rear and right side perspective view thereof.

1 Claim, 7 Drawing Sheets
